SALES AND ADVERTISING DISPLAY DEVICE

Emil N. Farkas and Frank F. Farkas, Chicago, Ill.

Application April 29, 1937, Serial No. 139,752

11 Claims. (Cl. 40—158)

Our invention relates to sales and advertising display devices and more particularly to a device for illustrating the details of construction, the assembly, the operation or any or all of them, of a desired apparatus, appliance, structure or the like. The invention has among its objects the production of a novel, attractive, convenient, simple, inexpensive, efficient and satisfactory sales display device for use wherever found applicable.

10 The invention has among its further objects the production of a device of the kind described that will simply and clearly display on suitably prepared pages or sheets, construction and assembly details of a desired structure, the manner or 15 order of assembly or disassembly, and in a preferred sequence, or the operation of the same, if an operating appliance.

Among its further objects is the construction of a device which provides all of the foregoing features and requires but a minimum, if any, detailed explanatory matter, the same being substantially illustratively self-explanatory, even to those of limited understanding.

A further object is the production of a device which may be employed as a construction, assembly or operating manual useful to obviate the necessity of sending expert or experienced workmen distances to set up or install apparatus, or to instruct inexpert local workmen in installation or operation.

30 A further object is to produce a device simply and inexpensively made up of cooperating parts which enter into the same including the employment of carrier pages for carrying extremely thin, transparent sheets which may be suitably imprinted and provide complete visibility through a comparatively large number of sheets. Imprints on underlying sheets are readily visible, thus permitting the assembly of a considerable 35 number of sheets or pages and showing of many detail illustrations in desired sequences.

Many other objects and advantages of the device herein shown and described will be obvious to those skilled in the art from the disclosure herein given.

45 To this end our invention consists in the novel construction, arrangement and combination of parts herein shown and described, and more particularly pointed out in the claims.

50 In the drawings, wherein like reference characters indicate like or corresponding parts:

Fig. 1 is a perspective view illustrating an embodiment of the invention;

Fig. 2 is a sectional view taken substantially on 55 line 2—2 of Fig. 1;

Fig. 3 is a perspective view, with a portion of one of the sheets broken away to show the construction;

Fig. 4 is a view in elevation of one of the pages showing its particulars with an imprint of an underlying page shown in dotted lines as it would appear when the page is superimposed over a preceding page;

Fig. 5 is a similar view also illustrating in dotted lines imprints on preceding pages;

Fig. 6 is a similar view illustrating the use of colors, etc., to display operation;

Fig. 7 is a view showing a succeeding page and illustrating a complete or finished device;

Fig. 8 is a perspective view of the sheet 40—42, and

Fig. 9 is a sectional view of a portion of several sheets to illustrate the use of the sheet 40—42.

To avoid confusion and misunderstanding, it may be mentioned that the particular apparatus shown in the imprints illustrated in the drawings is merely for illustrative purposes to show the construction purpose and use of our improved display device. Briefly, our device consists of a plurality of pages, preferably of similar construction and uniform size, each consisting of a relatively stiff sheet having a suitably shaped window with a very thin, transparent sheet extended over the window opening and upon which may be imprinted suitable and desired pictorial illustrations, so that as the pages are successively superimposed in registry one on the other in a predetermined order and relationship or sequence, there are displayed details of construction or operation as well as a more or less complete assembly, each page bearing an imprint illustrating one or more detail parts.

With our improved device it is possible and convenient to view designs or illustrations progressively one or several pages separately from all of the others or at any time quickly and conveniently to review any preceding page or series of pages, and then by turning or duplicating pages proceed to add more or remove, etc. In our invention we provide for absolute and interchangeable accuracy of position because our pages are substantially in actual contact, the imprinted designs or illustrations being accurately located on each sheet to provide for accurate registry with any preceding or succeeding illustration on another page. We can at all times on an earlier or later page present another object which may require positioning within the boundaries of another displayed illustration and subjects may overlap; that is to say, parts whose

55

boundaries pass in front or behind any other part, can be shown in its entirety. Our arrangement permits us to show on individual pages more detail of parts seen than would be visible of the part in viewing the whole.

Referring particularly to Figs. 1, 2 and 3, 1 represents a page of suitable material, preferably a somewhat stiff and durable but light-weight cardboard or the equivalent, the same having a portion within the confines removed to provide a window 7 of the desired size and shape, the body of the page forming a frame 9 for the window. Extending over the window is a sheet 8 of very thin, flexible, transparent material, such as "cellophane," "kodapack" (these being trade names for a suitable material now on the market), or similar equivalent thin-sheet, transparent material. The sheet of thin material designated by the numeral 8 on said figures is larger than the opening 7 and, if desired, may extend over the back or front to a desired distance from the outer edges of the frame portion 9 and be secured in place by any suitable adhesive. It is preferred to tension the transparent sheet when attaching 25 so that it is without wrinkles. It is desirable to use a very thin, as well as very clear, transparent material which, while difficult to handle by itself, may be readily handled when attached to the frame and upon which may be printed or otherwise applied suitable illustrations, the frame not only serving as a convenient carrier for the transparency for display purposes, but also during the imprinting of the illustrations on the transparency, to which latter further reference will be 35 hereinafter made.

Any desired number of sheets or pages may be prepared, only a few to illustrate the use of the device being shown in the drawings and indicated by the reference numerals 2, 3, 4 and 5 shown in 40 Figs. 5 to 7, inclusive. In these figures the window openings are all designated by the numeral 7 and the transparent sheets by the numerals 8², 8³, 8⁴ and 8⁵, respectively.

In making up the pages, the frames 9 are first 45 prepared with window openings and then the transparent sheets 8¹, etc. attached thereto at the back, providing a unitary structure. The desired pictorial illustrations are then imprinted on the transparent sheets in the proper location, the 50 same being of the desired size and color, so that when a number of sheets or pages are superimposed, the associated designs will properly register. In Fig. 1 we have shown an imprint 10, which in this particular case, represents the inner shell 55 of a heater, the shell being shown in section.

In Fig. 4, page 2, are shown imprints 11, 12, 13 and 14 which may be imprinted on the transparent sheet 8², representing piping or fittings. In this figure in dotted lines is shown the shell 10 60 which is displayed on another sheet, the purpose of showing the same in this figure being to illustrate how the various illustrations register and are visible when superimposed, as well as to show the appearance when pages are combined, in 65 which case of course, the shell 10 would show through the transparent sheet 8² as illustrated at 10 in Fig. 1.

Fig. 5, illustrating a page 3 with the transparent sheet 8³, shows the imprint of suitable insulation 70 15 and an outer shell 16 which are depicted on this page. This figure also shows in dotted lines the features illustrated in Figs. 1 and 4 as they would appear when the three sheets are superimposed one above the other with the imprints 75 in registry. Fig. 6, or page 4, shows the transpar-

ent sheet 8⁴. On this sheet it is shown how there may be imprinted suitable colored impressions as, for example, 17 and 18 of contrasting colors to show hot and cold water or other matters for the purpose of illustrating the operation of the device. In order to avoid confusion, it may be mentioned that outlines of the parts shown on the preceding sheets are shown in full lines on this figure. Some of these may be only visible through the transparent sheet, while others may be directly printed or reprinted on the transparent sheet, this being more or less immaterial.

In Fig. 7, upon which is shown page 5, there is shown a panel or imprint 19 intended to represent the exterior of the completed device. In this instance the impression may be opaque, so that only the exterior is shown with any piping projecting therefrom as may be desired. It is obvious that there may be any number of pages, this depending upon the apparatus to be displayed and the amount of detail features disclosed, as well as the various operations or assembly steps that it may be desired to show.

As shown in Figs. 1 and 4 to 7, inclusive, the frame portion 9 or the body part of the pages may have printed thereon suitable advertising, explanatory matter or illustrations of details as indicated at 20, or prices, dimensions and specifications, for example, which may be imprinted at 21, 22 or 23. Lead lines may run from the matter on the frame to the design sheet, or one page have indicia or characters to superimpose on a preceding design to identify parts. There may be additional pages which may be sheets without windows or with more or less opaqued windows to be placed in the beginning or at the end containing illustrations, descriptions, instructions or such other material as may be found desirable.

As was mentioned, the device is used by successively superimposing one page over the other, and to provide for registry of the pages so that the parts are in proper registry, we have shown the pages mounted on a backing 25 and secured thereto and to each other by suitable binder rings, spirals or the like 26, or any equivalent for the purpose. The backing 1 is shown with a cover supporting back 27 hinged thereto as indicated at 28 and with a base 29 preferably arranged to fold at 30. The base 29 may be provided with a groove as indicated at 31 for supporting the lower edge of 25 when the device is set up. The entire device may be folded in the form of a book. As shown in Fig. 1, we prefer to provide suitable guiding means, a simple and preferred construction being the fingers 32 secured to the backing 1 so that the pages are supported and maintained in proper relation at the top and aligned at the bottom and maintained in registry. Additional guides may be employed if desired. In using the device, the same may be set up substantially as shown in Fig. 1, with the various pages as shown at 2, 3, 4 and 5, etc. The material is displayed by turning the pages over successively onto the front pages supported on the backing 25.

We have shown in Fig. 1 a supplemental page or part which consists of an opaque page or sheet 40 folded back on itself as at 41 to provide a hinged flap or blank sheet 42 (see detail Fig. 8). Ordinarily this may be folded up as shown in Fig. 1 where not used. When it is desired to blank out or cover preceding sheets in order to more prominently display the illustration on the top sheet or sheets and confine the display entirely to the material on the top sheets, the portion 42 may be opened up and then folded back 75

so as to underlie the transparent sheet or sheets and illustration which are desired to display (see Fig. 9). The sheet or part 42 being blank and opaque the design on the outer display sheet or sheets stands out clear and by itself. This thereby enables one or more outer or top sheets to be isolated from preceding sheets that are under and conceal any desired sheets which are under.

It will thus be seen that as the pages are successively turned over there is displayed in regular predetermined order and relationship or sequence, details of construction, the method of assembly, or steps in the operation of any suitable apparatus, appliance or structure. The apparatus also lends itself well to illustrating details of building construction, or in teaching various courses. The uses of the device are practically without end and it is not considered necessary to endeavor to set forth any considerable number herein. It will be obvious that in setting up machinery or construction work, it is possible to prepare pages with suitable imprints which may be sent out on a job, enabling local labor to perform the work and without sending out special or expert workmen from a distance. In other words, it is possible to convey instruction visibly rather than by written explanation or information, which may be complex and perhaps difficult to clearly express, if not even entirely impossible. Of course such explanation as is desired may be put on the faces of the pages.

With our improved device it is possible to blank out or opaque any particular feature on one page or in lieu of printing or painting on the sheet to illustrate a picture of a detail by attaching the picture to the transparent sheet at either face so that it will properly register with an associated page, and then thereafter on a succeeding page restore the blanked out material as previously shown, or put in new or modified material. In other words, the construction is so extremely flexible it is possible to provide a wide range of illustrations and details without destroying the unit as a whole. We are not required to have a fixed, definite sequence but may freely vary or interchange the order of displaying our illustrations as may suit our convenience or purpose and may repeat or duplicate pages as may be found desirable to secure the desired result.

In making up the pages with the more or less stiff, rigid body consisting of a frame part 9 with the window or cut-out portion 7, it is possible to use the extremely thin and clear transparent sheets over the window, the thin sheets affording more transparency, permitting more pages or sheets to be combined than would be possible with thicker transparencies. This arrangement also facilitates the printing of the illustration on the very thin flexible material of the kind mentioned. At the present time such thin materials, owing to difficulty in handling, are printed from continuous sheets from rolls of material only on very costly presses, so that it is not commercially practical to print them except in large quantities. It is only by printing on continuous sheets and putting the sheets under tension to give the desired rigidity that such materials can be employed for printing purposes. We can readily tension the individual sheets as they are applied to the cardboard sheets. This is particularly true where printing is desired in several colors, and where accurate register of the successive printings is essential. Our invention provides a means for printing on such very thin, flexible, transparent materials on small commercial presses or even on simple

hand presses, thus affording a great saving in production costs and also making practical the printing on such sheets in small quantities. Heretofore, when it was necessary or desirable to print on transparent materials in small quantities on simple printing equipment, it could be done only by providing a heavy and relatively rigid sheet of transparent material. Thus the requisite firmness for feeding small area sheets and properly registering successive illustrations or colors could only be secured at great additional cost, owing to the higher price of the thicker materials, at the same time losing the desirable transparency of extremely thin material. By using our frame border of heavy and relatively rigid, inexpensive materials, as for example, cardboard, and by combining the lower cost of finer transparent material therewith, we have a gain in transparency, have rigidity, as well as reduced cost of materials and manufacturing costs.

It will be noted that with our cardboard sheets or pages provided with a window opening and a thin, transparent sheet extended over the opening, the imprint of the illustration or design on the sheet, on the one face, is substantially inset so that it is not so apt to be rubbed off or effaced, and this is also true if it is on the opposite side, since it is located within the confines of the window on an adjacent sheet. It is, therefore, immaterial on which side the imprints are placed on the transparent sheet or even if on both sides, as the same are protected. In actual practice it has been found that if an extremely fine transparent sheet is used, on fairly thin cardboard, when the pages are superimposed with the windows aligned, there is a static tendency for the thin, transparent sheets when arranged face to face to seem to attract each other and draw together, so that the thin sheets, while of course not in the same plane, are so close together that they substantially appear to be a single sheet, so that the various impressions seem to be on a single sheet. While this does not afford any effective perspective, this is immaterial and in fact preferred since any desired apparent perspective or depth on any particular illustration may be accomplished by shading or otherwise.

By covering the apertures with sheets of thin transparent material, the positioning of successive views to illustrate true relations of parts which overlap is accomplished without obstructing more than may be intentional of those parts illustrated on preceding pages.

We also produce pages suitable for use in an assembly of pages, easy to take hold of, sufficiently rigid to handle and turn over and stable in its own plane for suitable combination with other similar elements in a predetermined order and relationship or sequence and perfect registry with them. Still another advantage is that we acquire an area suitable for printing elaborate, fine color representations on the adjacent cardboard surfaces, supplementing the material on the transparent surfaces. It is not practical to print complex and fine process color effects upon celluloid or like surfaces and in this way we are able to employ supplemental effects, adding to the portrayal of the essential or the transparent portions. In connection with the printing of the devices, it will be obvious that the frame or stiff body of the page enables the page to be accurately located during printing, so that absolute registry on successive pages may be secured on the transparent portions. This is particularly important, if not essential, in color printing

where colors are successively applied and reprinting required.

Having thus described our invention, it is obvious that various immaterial modifications may be made in the same without departing from the spirit of our invention; hence we do not wish to be understood as limiting ourselves to the exact form, construction, arrangement and combination of parts herein shown and described, or uses mentioned.

What we claim as new and desire to secure by Letters Patent is:

1. In a selling display device of the kind described, the combination of a plurality of pages 15 hingedly secured together, each consisting of a stiff body sheet having an opening through the body of the same and providing an opaque frame about the opening, a thin transparent sheet of material capable of receiving an imprint extending 20 over the opening and secured to the stiff sheet at a plurality of points about the opening, the transparent sheets provided with impressions or imprints depicting certain portions of a device to be displayed partially or completely assembled, the imprints on the transparent sheets being so disposed on the same as to superimpose in registry and display relationship of the illustrated portions as the pages are successively turned to assemble the illustrated portions of the 30 device from the interior to the exterior of the same.

2. In a selling device of the kind described, the combination of a plurality of cooperating sheets of corresponding size, each consisting of a sheet 35 having a portion cut out to provide a window with a frame about the window, a tensioned sheet of thin transparent material mounted on a face of the sheet and extending over the window to provide a printing surface at the window, said transparent sheets having imprinted thereon representations of a portion of a complete device so arranged to be brought into a desired registry to perpetrate a unit device, whereby when the several sheets are superimposed the portions may 45 be successively brought into registry to display the several portions assembled in a completed unit.

3. A display device of the kind described, comprising a plurality of assembled leaves, means for hingedly connecting adjacent meeting ends of the leaves together at one end of the assembly, each leaf having a transparent portion, said transparent portions being positioned to superimpose one on another, figures imprinted on each 55 of said transparent portions and relatively positioned with respect to the figures on an adjacent other leaf, each figure depicting a detail element of a unit, and descriptive matter on the opaque portion of each leaf relative to the figure thereon, said leaves being adapted to be successively rotated in or out of superimposing relation.

4. The combination of a plurality of sheets of relatively stiff material, each having a portion cut out to provide a window opening, a sheet of 65 relatively thin, transparent material secured to one face of each of said first mentioned sheets and extending over the opening therethrough, and pictorial representations of objects constituting parts of a unit to be displayed imprinted on said transparent sheets, the various parts being distributed on different sheets, whereby a complete unit may be pictorially built up step by step by superimposing sheets to illustrate the construction of the unit, a substantially rigid back- 75 ing member, means for hingedly securing one

edge of each sheet to the backing member, means on the backing member for engaging edges of the pages and maintaining the displayed pages in alignment.

5. The combination of a plurality of sheets of relatively stiff material, each having a portion cut out to provide a window opening, a sheet of relatively thin, transparent material secured to one face of each of said first mentioned sheets and extending over the opening therethrough, and pictorial representations of objects constituting parts of a unit to be displayed imprinted on said transparent sheets, the various parts being distributed on different sheets, whereby a complete unit may be pictorially built up step by step by superimposing sheets to illustrate the construction of the unit, a substantially rigid backing member, means for hingedly securing one edge of each sheet to the backing member, and an opaque sheet associated with said windowed sheets for selectively covering any sheets underlying the same.

6. The combination of a plurality of sheets of relatively stiff material constituting pages, each having a portion cut out to provide a window opening, a sheet of relatively thin, transparent material secured to one face of each of said first mentioned sheets and extending over the opening therethrough, and pictorial representations of objects constituting parts of a unit imprinted on said transparent sheets, the various parts being distributed on different sheets, whereby a complete unit may be pictorially built up step by step to illustrate the construction of the unit, a substantially rigid backing member, means for hingedly securing one edge of each sheet to the backing member, means on the backing member for engaging adjacent edges and maintaining the pages in alignment, and foldable cover means hinged to said backing member adjacent the hinged edges of said sheets, said cover constituting a support for the back when the same is set up in operative display position.

7. A pair of cover members, a plurality of leaves, normally contained between said cover members, means for pivotally connecting the cover members and leaves together, each leaf having a corresponding transparent portion containing an illustration relatively positioned with respect to the illustration on another leaf, each illustration comprising a selected detailed element of a unit desired to display, and descriptive matter on the opaque portion of each leaf relative to the figure thereon, said leaves being adapted to be rotated in or out of superimposed relation.

8. The combination of a plurality of sheets of relatively stiff material constituting pages, each having a portion cut out to provide a window opening, a tensioned sheet of relatively thin, transparent material secured to one face of each of said first mentioned sheets, the same being spaced from the plane of the opposed face of the sheets and extending over the opening therethrough, and pictorial representations of objects imprinted on said transparent sheets and constituting parts of a unit to be illustrated, the various represented parts being distributed on different sheets, whereby a complete unit may be pictorially built up step by step to illustrate the construction of the unit, a substantially rigid backing member, means for hingedly securing one edge of each sheet to the backing member, a supplemental page of substantially the same size as the windowed pages similarly hinged to the

backing member, the supplemental page provided with an opaque extending part hinged to its free end and movable to selectively overlie any desired windowed pages and foldable cover means 5 hinged to said backing member and constituting a support for the back when the same is set up in operative display position.

9. The method of constructing a page for a display device of the kind described, consisting 10 in cutting the page from a relatively stiff paper sheet of a desired size and shape and cutting out a window opening within the confines of the sheet of a desired size and shape, thence cutting a sheet of very thin transparent material of 15 a size greater than the window opening in the cardboard, tensioning the transparent sheet so that it is taut over the opening and securing the edges to a face of the sheet to permanently combine the two sheets, thence imprinting a desired 20 design on a face of the transparent sheet after mounting on the paper sheet and within the confines of the opening, using edges of the stiff paper sheet as a guide for locating the design on the transparent sheet whereby when the paper sheet 25 is embodied in an assembly with other sheets the designs will register when superimposed.

10. The method of constructing a display de-

vice having pages of the kind described, consisting in blanking the pages from relatively stiff paper sheets and cutting out a window opening in each to provide a frame, then securing a very thin sheet of transparent material on a face of each paper sheet over the opening, then imprinting pictorial illustrations on each of the several transparent sheets in position to register with associated pictorial illustrations on a cooperating sheet, and combining the sheets together. 5

11. The method of constructing a display device having pages of the kind described, consisting in blanking the pages to a uniform size from a relatively stiff cardboard sheet with an 15 opening within the confines of each of the several pages to provide a window opening surrounded by a frame, securing a very thin sheet of transparent material of a size larger than the opening and extended over the opening to a face of each 20 of the stiff cardboard sheets, and thence using two edges of the cardboard as a guide, and thereafter successively printing different designs in color on the mounted transparent sheets.
